UNITED STATES PATENT OFFICE.

HAROLD E. WHITE, OF SCHENECTADY, NEW YORK, ASSIGNOR TO GENERAL ELECTRIC COMPANY, A CORPORATION OF NEW YORK.

MOTOR-CONTROL SYSTEM.

977,912.

Specification of Letters Patent.

Patented Dec. 6, 1910.

Application filed July 19, 1910. Serial No. 572,715.

To all whom it may concern:

Be it known that I, HAROLD E. WHITE, a citizen of the United States, residing at Schenectady, county of Schenectady, State of New York, have invented certain new and useful Improvements in Motor-Control Systems, of which the following is a specification.

My invention relates to motor controllers and its general object is to provide a new and improved apparatus in which means is included for preventing overloading of the motor by too rapidly increasing the potential applied thereto.

In general, my invention comprises a motor controller in which movable contact members are successively brought into engagement with other contact members, and in which means responsive to conditions in the motor circuit is provided for holding certain of the last-mentioned contact members out of coöperative relation to the other contact members during overload conditions in the motor circuit.

My invention will be fully understood from the following description and drawings, in which one embodiment of it is set forth.

In the drawings, Figure 1 is an elevation partly in section, of a controller having my invention embodied therein; Fig. 2 is a sectional plan view of said controller on the line A, A of Fig. 1; Fig. 3 is a view, similar to Fig. 2, but with the controller shaft rotated through an angle of 90°; Figs. 4, 5 and 6 are sectional plan views through the controller shaft showing the form of the segments mounted thereon, and Fig. 7 is a diagram representative of the controller and the motor circuits controlled by it.

I have shown my invention as embodied in a controller of the drum type but of course it may be incorporated in many other kinds of control apparatus. Referring to the drawing, and particularly Figs. 1, 2 and 3, the contact members of the controller are shown as located within a casing 8 having a cover 9. The main shaft 10 of the controller carrying the handle 11 is journaled in the cap plate 12 and in the base 13 in any suitable and well-known manner. The usual star-wheel is shown at 14 and its coöperating follower at 15. The shaft 10 carries body members hereinafter referred to which may be secured to an insulating sleeve 16 keyed

to said shaft in a well-known manner. In the controller shown there are five contact segments *a*, *b*, *c*, *d* and *e*; and these contact segments coöperate with fingers *a'*, *b'*, *c'*, *d'* and *e'*. The two upper segments *a* and *b* and their coöperating fingers *a'* and *b'* may be of any suitable and well-known form. The three lower segments *c*, *d*, and *e* and their coöperating fingers *c'*, *d'* and *e'*, which regulate the amount of resistance in the motor circuit, are of a new form, which will now be described.

The segments *c*, *d* and *e* are shown respectively in Figs. 4, 5 and 6 as mounted upon body members of insulating material 18, 19 and 20, which are of the form shown. These body members 18, 19 and 20 act as cams and engage the coöperating contact fingers *c'*, *d'* and *e'* in the manner hereinafter explained. These contact fingers are 75 movable and in the present construction are pivotally supported. In the drawing the contact finger *c'* only is illustrated, but it is to be understood that the fingers *d'* and *e'* are similar. The finger *c'* is mounted 80 upon an armature 21 pivoted at 22 on the magnet frame 23, and said armature operates with an electromagnet having a magnetizing coil 24 mounted as shown on a core extending from the frame 23. This 85 frame 23 may be secured to the casing 8 in any suitable manner. The armature 21 carrying the contact finger *c'* is biased away from the pole of the electromagnet by a spring 26 arranged as shown. With this 90 arrangement the contact finger *c'* engages with the cam surface of the body member 18 which carries the contact segment *c*, and when said finger is engaged by said cam the armature 21 is substantially in engagement 95 with the pole of the electromagnet. When, however, rotation of the shaft 10 has moved the cam out of engagement with the contact finger *c'*, said finger under the influence of the spring 26 will be moved into engagement with the contact segment *c*, unless it is held out of engagement by the magnetizing effect of the electromagnet upon the armature 21. Fig. 2 shows the contact finger *c'* in engagement with the cam surface 100 of the body member 18, and Fig. 3 shows the contact finger in engagement with the contact segment *c*. The forms and relation of the body members 18, 19 and 20 which carry the contact segments *c*, *d* and *e* are 105 110

shown in Figs. 4, 5 and 6, and it will be obvious that as the shaft 10 is turned the fingers c' , d' and e' one after another are released by the cams and are free to move 5 into engagement with their coöperating contact segments c , d and e unless they are held out of such engagement by their respective electromagnets. Of course, instead 10 of a plurality of magnet coils, I may employ but one arranged to produce a magnetic field which affects all the armatures.

The arrangement of circuits and mode of operation will best be understood from an inspection of Fig. 7. In this figure the controller is diagrammatically illustrated as arranged to control the motor M for one direction of rotation, three sections of resistance R^1 , R^2 and R^3 being shown. The contact segments and their supporting body 15 members which act as cams are shown conventionally as developed on a plane surface and the contact fingers are also shown in a conventional manner. In order to facilitate diagrammatic illustration the fingers c' , d' 20 and e' are shown as carried by longitudinally movable cores instead of pivoted armatures, these cores being biased toward the contact segments by springs and said cores being arranged for movement in the fields 25 of electromagnets having their windings energized from the motor circuit by being connected permanently in series with one another and all in shunt to the resistance R^1 , R^2 and R^3 . In order to avoid confusion I 30 have used the same reference characters in Fig. 7 as in the other figures to denote corresponding parts. The segments a , b , c , d and e are connected electrically together, the upper finger a' is connected to the source 35 L , and the other fingers are connected to the various circuits in the manner clear from the diagram. For the sake of simplicity the motor has been shown with a ground return.

The mode of operation of the above described system is as follows: As the system is shown in Fig. 7, the controller handle is in the "off" position and the motor is disconnected from the source. When the handle is moved to bring the controller segments 45 to the position indicated by the line w , a circuit is completed from the source L through finger a' , segment a , segment b , finger b' , resistance R^1 , R^2 and R^3 and motor M to ground. Current also passes through the 50 magnets 24 which are connected in series with one another and in shunt to the resistance R^1 , R^2 and R^3 . These magnets are connected across the source in series with the motor and, therefore, receive current 55 which is proportional to the differences between the potential of the source and the potential of the motor. As long as the controller handle is in this position, the motor will operate with all the resistance in its circuit. When, however, the handle is moved 60

to the position x , the contact finger c' , is no longer engaged by the coöperating cam surface of the supporting member 18, and said finger is free to move into engagement with the segment c under the influence of the 65 spring 26 unless the coöperating magnet 24 is sufficiently energized to maintain the armature 21 attracted to it. In practice this magnet is so designed that it will hold said armature to it as long as the potential across the motor terminals is below a certain value, which means that an overload condition exists in the motor circuit. When, however, the motor potential rises above the value I have mentioned, the current in the upper 70 magnet coil is so reduced that the magnet releases the armature and the finger c' moves into engagement with the segment c , thereby short-circuiting the section of resistance R^1 . As long as the controller remains in the 75 position x , the motor will operate with only the sections of resistance R^2 and R^3 in its circuit. Further movement of the controller to the positions y and z will result in bringing the fingers d' and e' into engagement with their coöperating segments d and e , this action taking place, however, under the control of the coöperating electromagnets exactly as in the case of the finger c' just described. Of course, if desired, the 85 controller may be immediately thrown to the position z , whereupon the fingers c' , d' and e' will come into engagement with their coöperating segments one after another under the control of their electromagnets. These 90 magnets are so designed that the fingers c' , d' and e' will be released in succession when the potential of the motor has risen to successively higher values, at each of which the current in the motor circuit may be substantially the same owing to the constantly decreasing amount of resistance in the motor 95 circuit. Of course, if desired, the magnet coils may be connected directly in the motor circuit, or they may be connected in shunt to a special resistance, or a portion of the main starting resistance located in the motor circuit. When the controller is thrown back toward the "off" position, the cam surfaces of the supporting members 18, 19 and 20 100 engage with the fingers c' , d' and e' and successively move said fingers into the position illustrated in Fig. 2 in which the armatures carrying said fingers are in engagement with the poles of their coöperating magnets. 105

In the arrangement shown in this application, I have provided cams for moving the contact fingers to the position in which they are held by their coöperating magnets when the current in the motor circuit exceeds a 110 certain value, because such cams may under some conditions render the arrangement more positive in its operation. It is of course obvious, however, that said cams might be omitted and the magnets so de- 115

signed that the armatures carrying the contact fingers will not only be held by said magnets in a certain position but will also be attracted and actually moved by said magnets when the potential of the motor is below a certain value. Even when cams are employed as shown, the magnets operate to a certain extent to cause movement of the fingers, as well as to hold said fingers in a certain position.

It is evident that my invention may be embodied in a great variety of control arrangements without departing from the spirit thereof. The controller which I have shown is exceedingly simple and I have omitted all such features such as reversing drum, blow-out devices, etc. Of course, instead of effecting the connections in the motor circuit directly in the controller, said controller may be used as a master-switch and contactors employed in a well-known manner. It is my intention to cover all such arrangements in the following claims.

What I claim as new and desire to secure by Letters Patent of the United States, is:

1. A motor controller having movable contact members, contact fingers coöperating therewith, and means responsive to conditions in the motor circuit for holding said fingers out of engagement with said contact members during overload conditions in the motor circuit.

2. A motor controller having movable contact members, contact fingers coöperating therewith, means for moving said contact fingers into an inoperative position, and means responsive to conditions in the motor circuit for holding said fingers in this inoperative position and out of engagement with said movable contact members during overload conditions in the motor circuit.

3. A motor controller having movable contact members, contact fingers coöperating therewith, means moving with said movable contact members for moving said fingers into an inoperative position and holding them in said position while said contact members are not in a position to cooperate with said fingers, and means responsive to conditions in the motor circuit for holding said fingers out of engagement with said contact members after said fingers are released by said last mentioned means during overload conditions in the motor circuit.

4. A motor controller having movable contact segments, movable contact fingers

coöperating therewith, and magnetic means responsive to conditions in the motor circuit for holding said fingers out of engagement with said segments during overload conditions in the motor circuit.

5. A motor controller having movable contact segments, movable contact fingers coöperating therewith, and magnets energized from the motor circuit for holding said fingers out of engagement with said segments during overload conditions in the motor circuit.

6. A motor controller having movable contact segments, contact fingers coöperating therewith, means for moving said contact fingers out of operative position, and magnets energized from the motor circuit for holding said fingers out of operative position and out of engagement with said movable contact members during overload conditions in the motor circuit.

7. A motor controller having movable contact segments, movable contact fingers coöperating therewith, cams arranged to move said fingers into an inoperative position while said contact members are not in a position to coöperate with said fingers, and magnetic means energized from the motor circuit for holding said fingers in said inoperative position during overload conditions in the motor circuit.

8. A motor controller having contact segments mounted on a rotatable shaft, pivoted contact fingers coöperating with said segments, and magnetic devices energized from the motor circuit for holding said fingers out of engagement with said segments during overload conditions in the motor circuit.

9. A motor controller having contact segments mounted upon a rotatable shaft, pivoted contact fingers coöperating with said segments, cams carried by said shaft for holding said fingers out of coöperative relation to said segments just before said segments during the "on" rotation of the shaft come into coöperative relation with said fingers, and magnets energized from the motor circuit for holding said fingers in the position to which the cams move them independently of said cams during overload conditions in the motor circuit.

In witness whereof, I have hereunto set my hand this 18th day of July, 1910.

HAROLD E. WHITE.
